UNITED STATES PATENT OFFICE.

EDMUND HIGGINS, OF SOLDIERS HOME, CALIFORNIA.

COMBINED TABLE AND DESK.

No. 874,846.

Specification of Letters Patent.

Patented Dec. 24, 1907.

Application filed July 30, 1907. Serial No. 386,227.

To all whom it may concern:

Be it known that I, EDMUND HIGGINS, a citizen of the United States, residing at Soldiers Home, in the county of Los Angeles and State of California, have invented a new and useful Combined Table and Desk, of which the following is a specification.

This invention has reference to improvements in combined tables and desks, and is 10 designed to produce a desk on which heavy volumes may be easily secured and read without the necessity of bending over the desk.

The object of the invention is to produce a desk having a top which may be tilted to various degrees from the horizontal for convenience in reading a book placed upon the top, and which may also be brought to a nearly vertical position so that the top may be utilized as an easel for artists, sign writers and 20 others. In addition to this, the structure is so arranged as to provide a secret compartment not at all liable to be found by any one unacquainted with the structure of the desk.

The invention consists essentially in a desk 25 body having a top movable about a center so as to be tilted to a convenient inclination for reading, and the top is also movable about another center so as to be tilted into a nearly vertical position for use as an easel.

30 The moving top is provided with a curtain extension so arranged as to hide the interior of the body as the top is tilted, and beneath this curtain there is arranged a secret compartment having a cover which is accessible 35 when the curtain is removed, while the upper wall of the secret compartment may be so formed as to in part constitute a rack for holding the top in the inclined positions to which it is adjustable.

40 The invention will be fully understood from the following detailed description, taken in connection with the accompanying drawings forming part of this specification, in which,—

45 Figure 1 is a perspective view of the combined desk and table, showing the desk structure projected; Fig. 2 is a vertical section through the structure, showing the top moved to an inclination; Fig. 3 is a perspective view 50 of the latch mechanism for holding the top in the inclined positions; and Figs. 4 and 5 are detail views.

55 Referring to the drawings, there is shown a desk frame consisting of hollow end pedestals 1 which may, if desired, be made sufficiently wide to receive drawers in the usual

manner, and the pedestals are joined by a back 2 and suitable cross bars 3, together with a bottom 4 and an intermediate shelf 5, as well as a front connection 6. The whole 60 structure may rest upon casters 7 in the usual manner.

Housed in the space between the pedestals is a desk structure consisting of sides & pivoted at their lower ends, as shown at 9, to a 65 fixed portion of the pedestals, and these sides are connected by a top frame 10 and an ornamental front 11. The top frame is provided with a depressed portion 12 for the reception of stationery and the like, and this frame has 70 an opening normally closed by a cover 13. Within the receptacle 12 may be located an inkwell 14 having a closure 15 at the upper end. The frame 10 is hinged at 16 to the front corners of the sides 8 and the other end 75 of the frame is provided with rollers 17 moving in guides 18 formed in the upper portion of the top of the desk structure, so that when the sides 8 of the desk structure are drawn outward the frame 10 is carried therewith 80 and ultimately engages the tops of these sides 8, when the cover 10 and frame 13 will rest in an inclined position appropriate for a person seated in a chair and at about the proper height and slant for a person desiring to use 85 the desk for writing.

The body portion is continued upward above the desk receiving portion, and is provided with arc-shaped upper ends 19 struck from a center determined by pivots 20, to be 90 hereinafter referred to. Fitted to the upper end of the body is a rectangular top 21 having sides with walls curved on arcs struck from the pivots 20, as shown at 22, and the curved edges 22 rest upon the arc-shaped or 95 curved edges 19. At each end of the top 21 are guide plates 23 extending downward a short distance along the ends of the pedestals of the desk, so that the top is prevented from moving longitudinally with relation to the 100 desk, and exterior to these guides are other side extensions 24 to which are pivoted arms 25, and these arms, in turn, are mounted upon the pivots 20. The other ends of the arms 25 are offset, as shown at 26, and curved upon 105 a center determined by a pivot 27 connecting the arms 25 and side extensions 24.

Now, let it be supposed that the top 21 of the structure, which constitutes the book-holding top for reading purposes, is moved 110 about the pivots 20 as an axis. It will be seen that this top will be brought to an in-

clined position and may be moved in such direction until the arms 25 meet stops 28 and their motion is then arrested. However, the top may still be turned about the pivots 27, 5 and the structure is such that when the motion of the arms 25 is arrested by the stops 28 the top may then be turned about the shorter axis determined by the pivots 27 and be allowed to assume a nearly vertical position 10 along the front of the pedestals. When in this position the top may be held by extensible brackets 29, normally housed in the pedestals and pivoted thereto at their lower ends, while the extent of projection of these 15 brackets is determined by stops 30 carried thereby and engaging the front walls of the pedestals where the brackets project through the latter. Each bracket is provided with a knob 31 for convenient manipulation. The 20 brackets are so constructed that when projected their upper edges are horizontal. By moving the engaging edge of the top along the upper edge of the brackets 29 away from the body of the structure, the inclination of 25 the working face of the top section of the table may be adjusted at will.

Along one edge of the working face of the top 21 is a ledge 32 against which may rest the edge of a book, such as indicated at 33, 30 and a cord 34 may be provided for holding the leaves of the book in position, and for other purposes, or more than one cord may be provided if so desired. When the top is 35 in the nearly vertical position for use as an easel the ledge 32 will serve as a support for anything placed upon the easel, while the cord or cords 34 may then be utilized to hold the painting or sign or whatever else may be placed on the easel, in place.

40 Just above the frame 10 and housed in the body of the structure is a plate 35, between which latter and the adjustable top there remains a considerable space. This space is utilized as a secret compartment by placing 45 above the plate 35 a curved wall 36 having one section 37 constituting about one-half of the wall 36 hinged thereto, as shown at 38. The hinge or hinges are arranged longitudinally with reference to the wall 36, so that 50 when the front end of the section 37 is raised access is had to the space beneath the wall 36 and between it and the plate 35. Suitable latches 39 may be provided for holding the hinged section or door 37 closed.

55 Mounted in the top portion 21 at the rear edge thereof is a curtain roller 40 carrying a curtain 41, the free end of which may be provided with hooks 42 to engage pins 43 on the body portion of the structure, so that when 60 the top portion 21 is adjusted to various degrees of inclinations the curtain 41 will be withdrawn from the roller 40 and overspread the wall 36, thus hiding it from view and also concealing the fact that this wall covers a 65 secret compartment. The secrecy of this

compartment may be further provided for by placing the hinges 38 on the inner or concealed side of the wall 36, so that even were an observer to see the division line between the cover section 37 and the remainder of the 70 wall 36 there would be no intimation that this constituted a hinged section which could be opened.

The wall 36, with its hinged section 37, near each end is formed with series of ratchet 75 teeth 44 in which normally engage pawls 45 fast on a plate 46 hinged on a rod 47 extending through the top 21. The pawl-carrying plate 46 is engaged by the angle ends 48 of rods 49 suitably supported in eyes or brackets 50 fast in the top of the structure. These rods 49 extend to and through the front panel 51 of the top 21 and are there turned at an angle, as shown at 52, for easy manipulation. The rods 49 are disposed at each end of the 85 top section 21 and between them this top section may be provided with a drawer 53.

When it is desired to tilt the top 21 the two ends 52 of the rods 49 may be grasped by the hands of the user and turned on their 90 longitudinal axes. This will cause the angle ends 48 to lift the pawl plate 46 and elevate the pawls 45 out of engagement with the ratchet teeth 44. Now, by pulling upon the handle ends 52 of the rods 49 the top may be 95 tilted forward as far as desired, when the rods 49 may be returned to their normal position, thus releasing the plate 46 and permitting the pawls 45 to drop into engagement with the teeth 44. Under these conditions 100 the top 21 will remain in the inclined position, being held there by the pawls 45, until the latter are again released from the teeth, when the top may be further tilted. It may, however, be pushed back to its normal horizontal position without manipulating the rods 49, since the pawls 45 are free to move upward from the teeth. When the top is 105 moved backward to its normal position the roller 40, which is of the spring roller type, 110 will rewind the curtain 41.

When it is desired to gain access to the secret compartment the curtain may be unhooked from the pins 42 and the top brought to the position shown in dotted lines in Fig. 115 2, resting on the brackets 29. The cover 37 is then exposed to view and by manipulating the latches 39 to release the cover the latter may be lifted and access to the secret compartment may be had.

I claim:—

1. The combination in a desk, of a main frame, pivot members carried thereby, the top of the frame being arranged on a curved line struck from the center of said pivots, 125 an adjustable top section, arms mounted on said pivots, pivotal connections between the arms and the top section, a rack carried by the main frame, and a pawl carried by the top section and engaging said rack. 130

2. The combination in a desk, of a main frame, an adjustable top section, pivotal connections between the top section and the main frame whereby the top section may be moved to different degrees of inclination, and supports on the main frame for receiving the top section when moved to a substantially upright position.
3. The combination in a desk, of a main frame, pivot arms carried thereby, an adjustable top section pivotally secured to the pivot arms, and pawl-and-ratchet adjusting means for the top section
4. The combination in a desk, of a main frame, pivot arms carried thereby, a top section, the meeting edges of the top section and main frame being curved on an arc struck from the axis of the pivotal connections between the arms and the main frame, pawl-and-ratchet detents for holding the top in the adjusted positions, and brackets carried by the main frame for supporting the top when moved to one side of the main frame.
5. In a desk, a main frame, a top therefor movable with relation to the main frame and from engagement with the upper end thereof, a compartment concealed between the top of the desk and the main frame and carried by said main frame, and a member connected to the desk top and movable thereby over and concealing the compartment when the said desk top is moved with relation to the main frame.
6. In a desk, a main frame, a top therefor movable with relation to the main frame and from engagement with the upper end thereof, a compartment provided with a hinged cover and concealed between the top of the desk and the main frame and carried by the lat-
- ter, and a concealing curtain carried by the top section and attached to the main frame and covering the compartment when the top section is moved with relation to the main frame.
7. The combination in a desk, of a main frame, an adjustable top section therefor, a compartment in the main frame concealed by the top section, a curtain carried by the top section and arranged to cover the compartment when the top section is adjusted with relation to the main frame, ratchet teeth formed in the walls of the compartment, and pawls carried by the top section and engaging said ratchet teeth
8. The combination in a desk, of a main frame, an adjustable top section therefor, a compartment in the main frame concealed by the top section, a curtain carried by the top section and arranged to cover the compartment when the top section is adjusted with relation to the main frame, ratchet teeth formed in the walls of the compartment, pawls carried by the top section and engaging said ratchet teeth, and means for operating said pawls to release the top section from engagement with the ratchet teeth, comprising rotatable rods having angle ends for moving the pawls out of engagement with the teeth and having other angle ends exterior to the top and constituting manipulating handles.

In testimony that I claim the foregoing as my own, I have hereto affixed my signature in the presence of two witnesses

EDMUND HIGGINS.
